Primary Examiner—Alan P. Douglas*Assistant Examiner*—Angela J. Lee(74) *Attorney, Agent, or Firm*—Nancy N. Quan; Michael Bergman(57) **CLAIM**

The ornamental design for a support structure for a lamp for dentistry applications, as shown and described.

DESCRIPTION

FIG. 1 is a front perspective view of a support structure for a lamp for dentistry applications, said drawing showing a lamp and a control module therefore attached to a support structure for a lamp for dentistry applications embodying our new design, wherein the lamp control module are shown in broken lines for illustrative purposes only and forms no part of the claimed design;

FIG. 2 is a left front perspective view thereof;

FIG. 3 is a right front perspective view thereof; and,

FIG. 4 is a top view thereof.
